(57) **CLAIM**

The ornamental design of a basin, substantially as shown and described.

DESCRIPTION

FIG. 1 is a perspective view of a basin and counter showing one embodiment of the new design;

FIG. 2 is a top view of the basin of FIG. 1;

FIG. 3 is a side view of the basin and counter of FIG. 1;

FIG. 4 is a front view of the basin and counter of FIG. 1;
FIG. 5 is a perspective view of a basin and counter showing a second embodiment of the new design;

FIG. 6 is a second perspective view of the basin and counter of FIG. 5;

FIG. 7 is a front view of the basin and counter of FIG. 5;

FIG. 8 is left side view of the basin and counter of FIG. 5;

FIG. 9 is right side view of the basin and counter of FIG. 5;

FIG. 10 is a top view of the basin and counter of FIG. 5;

FIG. 11 is a perspective view of the basin of FIGS. 1 and 5;

FIG. 12 is a top view of the basin of FIGS. 1 and 5;

FIG. 13 is a left side view of the basin of FIGS. 1 and 5, the right view being a mirror image thereof; and,

FIG. 14 is a front view of the basin of FIGS. 1 and 5.
